UNITED STATES PATENT OFFICE

JAMES W. ARROWSMITH, OF MORRISTOWN, NEW JERSEY.

INSTEP-ARCH SUPPORT.

1,055,306.

Specification of Letters Patent.

Patented Mar. 11, 1913.

Application filed August 5, 1911. Serial No. 642,508.

To all whom it may concern:

Be it known that I, JAMES W. ARROWSMITH, a citizen of the United States, residing in the town of Morristown, county of Morris, and State of New Jersey, have invented certain new and useful Improvements in Instep-Arch Supports, of which the following is a specification.

My invention relates to supports for the arch of the human instep, and its objects are among others to strengthen the support and render it more elastic and durable and more adaptable to the various forms of insteps requiring a support.

15 The improvements consist in the construction, combination and arrangement of parts hereinafter described and claimed and illustrated in the accompanying drawings.

In the said drawings, Figure 1 is an underside view of an instep support embodying the improvements; Fig. 2 is a vertical cross section on the line 2-2 of Fig. 1; Fig. 3 is a perspective of the brace or "underbridging" forming a part of the support.

25 The present invention is in the nature of an improvement on the support shown in Patents No. 717,523 granted to me January 6, 1903, and No. 748,553 granted to me December 29, 1903. In these patents is shown 30 an arch support with a slotted side portion and a reinforcing strip secured to the body of the support, the latter patent having this reinforcing strip on top of the main plate and the former having it beneath the main 35 plate and between the slotted portion and the opposite edge of the support. These forms of support have many advantages, and it has been found that the durability of the main plate is greatly increased by the use of 40 the reinforcing strip. However, numerous difficulties have arisen, and among them are the difficulty of so constructing and arranging the reinforcing piece or "underbridging" that it will not cause the fingers formed 45 by the slitting of the upturned side portion to bend over its inner edge and crystallize and break off, and the difficulty in constructing the "underbridging" so that it will not itself crystallize and crack transversely.

50 The present support is designed to give all the advantages of the reinforced supports of the patents above referred to and at the same time provide a spring contact between the reinforcing strip and the base of the 55 fingers and strengthen the reinforcing strip so that it will not crystallize along its inner

edge and give way beneath the weight of the wearer.

The main metallic plate A is arched to approximate the arch of the instep and is provided with an upturned side portion B divided into spring fingers B' by slits running into the body of the main plate. The main plate and side portion are provided with a cover F of non-metallic, flexible material secured thereto by the rivets D.

The spring reinforcing strip C is secured to the underside of the main plate at its ends by the rivets D and bridges the arch of the said plate. It is substantially triangular in form, having its greatest width and the apex of the triangle in the middle of the arch of the main plate. On the inner edge of this reinforcing strip C is a rolled-over portion E, integral therewith and extending over the said strip approximately half its mean width. This rolled-over portion has its greatest width at the middle of the reinforcing strip and opposite the apex of the triangle, and from there tapers toward each end, terminating a short distance from the ends of the strip. Its upper surface E' is substantially flat, to correspond with the under surface of the main plate immediately above it, and its outer edge rises gradually from the ends toward the center, leaving a space between the said outer edge and the strip, as shown at X.

It will be seen that the reinforcing strip with the rolled-over inner edge extending over a portion of its upper surface provides a support for the arch of the main plate and also a spring support for the portion of the main plate at the base of the slotted side portion, at which point the contact between the reinforcing plate and the main plate covers a considerable area and extends from end to end of the side portion along the line of junction of the said side portion and main plate. The effect of this construction is to reinforce the plate along the line of junction and for an appreciable distance on both sides of said line in such a manner that no fulcrum is given for the fingers composing the side portion to bend sharply and thus form lines of crystallization. The formation of the rolled-over portion at the inner edge of the reinforcing strip also provides a reinforcement and support increasing in strength and resiliency from both ends toward the middle to receive a part of the weight of the wearer when the main plate

and side portion are depressed. The upward curvature of the part E is on a smaller radius than the upward curvature of the main plate A above it, and the main plate is not, therefore, brought in contact with this part between its ends and its medial part until it has been depressed by the weight of the wearer to a certain extent. This tends to give this portion of the support greater elasticity as well as durability.

10 What I claim is:

1. An arch-support comprising a plate formed to approximate the under surface of the human instep-arch, an upturned side portion formed to approximate the side portion of the said instep-arch, a series of slits extending from the outer edge of said upturned side portion to the interior of the plate and dividing it into spring fingers, a reinforcing strip extending from a point near one end of the main plate to a point near the opposite end and connected therewith at its ends, said reinforcing strip having a portion at its edge along the line of junction of the body and side portion folded over and projecting between the plate and body of the reinforcing strip along substantially the length of the side portion, the inner edge of said folded over portion being out of contact with the body of the reinforcing strip and its upper surface being substantially parallel with the adjacent under surface of the plate.

2. An arch-support comprising a plate formed to approximate the under surface of the human instep-arch, an upturned side portion formed to approximate the side portion of the said instep-arch, a reinforcing strip extending from a point near one end of the main plate to a point near the opposite end and connected therewith at its ends, said reinforcing strip having a portion at its edge along the line of junction of the body and side portion folded over and projecting between the plate and body of the reinforcing strip along substantially the length of the side portion, the inner edge of said folded over portion being out of contact with the said body of the reinforcing strip near the middle, and its upper surface being substantially parallel with the adjacent under surface of the plate.

3. An arch-support comprising a plate formed to approximate the under surface of the human instep-arch, an upturned side portion formed to approximate the side portion of the said instep-arch, a reinforcing strip extending from a point near one end of the main plate to a point near the opposite end and connected therewith at its ends, said reinforcing strip having a portion at its edge along the line of junction of the body and side portion folded over and projecting between the plate and reinforcing strip along substantially the length

of the side portion, the inner edge of said folded over portion being out of contact with the body of the reinforcing strip near the middle.

4. An arch-support comprising a plate 70 formed to approximate the under surface of the human instep-arch, an upturned side portion formed to approximate the side portion of the said instep-arch, a reinforcing strip extending from a point near one 75 end of the main plate to a point near the opposite end and connected therewith at its ends, said reinforcing strip having a portion at its edge along the line of junction of the body and side portion folded over and projecting between the plate and body of the reinforcing strip along substantially the length of the side portion.

5. An arch-support comprising a plate 85 formed to approximate the under surface of the human instep-arch, an upturned side portion formed to approximate the side portion of the said instep-arch, a longitudinal reinforcing strip extending from a point near one end of the main plate to a point 90 near the opposite end and connected therewith at its ends, said reinforcing strip having a portion at its edge along the line of junction of the body and side portion folded over and projecting between the plate and reinforcing strip along substantially the 95 length of the base of the side portion, the inner edge of said folded over portion being out of contact with the body of the reinforcing strip and its upper surface being substantially parallel with the adjacent under surface of the plate, but out of contact therewith between its middle and its ends.

6. An arch-support comprising a plate 105 formed to approximate the under surface of the human instep-arch, an upturned side portion formed to approximate the side portion of the said instep-arch, a longitudinal reinforcing strip having a portion at its edge along the line of junction of the body 110 and side portion folded over and projecting between the plate and body of the reinforcing strip along the base of the side portion and terminating beneath said body.

7. An arch-support comprising a plate 115 formed to approximate the under surface of the human instep arch, an upturned side portion formed to approximate the side portion of said instep-arch, a series of slits 120 extending from the outer edge of said upturned side portion to the interior of the plate and dividing it into spring fingers, a reinforcing strip extending from a point near one end of the main plate to a point near the opposite end and connected therewith, said reinforcing strip having a portion of its edge along the line of junction of the body and side portion folded over 125 and projecting toward the opposite side and covered by its body.

8. An arch-support comprising a plate formed to approximate the under surface of the human instep-arch, an upturned side portion formed to approximate the side portion of the said instep-arch, said upturned side portion being provided with cuts through the metal thereof, a reinforcing strip extending from a point near one end of the main plate to a point near the opposite end and connected therewith at its ends, 10 said reinforcing strip having a portion at its edge along the line of junction of the body and side portion folded over toward the opposite edge along substantially the 15 length of the side portion.

9. An arch-support comprising a plate formed to approximate the under surface of the human instep-arch, an upturned side

portion formed to approximate the side portion of the said instep-arch, a reinforcing strip extending from a point near one end of the main plate to a point near the opposite end and connected therewith near its ends, said reinforcing strip having a portion at its edge along the line of junction 20 of the body and side portion folded over and projecting in the direction of the opposite edge along substantially the length of the side portion.

Witness my hand this 2nd day of August 30 1911, at the city of New York, in the county and State of New York.

JAMES W. ARROWSMITH.
